SEWING MACHINE BOBBIN WINDER

Clarence S. Best, Belvidere, Ill., assignor to
National Sewing Machine Company, Belvidere,
Ill., a corporation of Illinois

Application June 18, 1945, Serial No. 600,128

3 Claims. (Cl. 242—20)

1

This invention relates to sewing machines, and particularly to improvements in bobbin winders for sewing machines.

The main object of the invention is to provide a bobbin winder which is efficient for its intended purpose and dependable in operation; which functions to wind thread upon a spool in regular and uniform rows, in which the turns given the thread are regular and uniform, and which avoids piling up of thread at the ends of the spool.

In the winding mechanism embodying my invention, the thread distributor is moved back and forth in a single plane parallel with the axis of the spool, instead of in an arcuate path as is common in the art. By this construction, the thread distributor presents the thread to the spool in a uniform manner throughout the length of the spool, maintaining identical relationships and tension throughout the extent of the travel of the distributor opposite the spool. These advantages are not attainable when the distributor is moved back and forth in an arcuate path and the thread is not presented to the spool in a single plane parallel with the axis of the spool.

Another object of my invention is to provide positively synchronized driving means for rotating the spool and reciprocating the thread distributor, whereby the uniformity of the turns and rows of thread placed on the spool will be maintained.

Other objects and advantages will appear from the following specification.

In the drawings:

Fig. 1 is an elevational view of a sewing machine provided by a bobbin winder embodying my invention.

Fig. 2 is an elevational view of part of one end of the machine, on an enlarged scale, showing part of the upright standard and fly wheel, and showing in end elevation my improved bobbin winder mounted on the face of the standard.

Fig. 3 is a longitudinal, vertical sectional view, partly in elevation, of the bobbin winder.

Fig. 4 is a transverse, vertical sectional view taken in the plane of the line 4—4 of Fig. 3.

Fig. 5 is a perspective view of a detail of construction.

Fig. 6 is a sectional view of a detail of construction taken in the plane of the line 6—6 of Fig. 4, looking in the direction indicated by the arrows.

Conventional parts of a sewing machine head to which my invention may be applied include the bed plate 10, upright standard 11, overhanging

arm 12, sewing head 13, fly wheel 14 and spool carrying spindle 15.

In the preferred embodiment of my invention shown in the drawings, the bobbin winder comprises a specially formed bracket having a base 16, and arms 17 and 18 rising from the base 16 at opposite ends thereof. The arm 17 has an upper portion 19 horizontally bored to serve as a journal for the shaft 20 of the pulley 21, the pulley 20 being adapted for contacting the fly wheel 14 when the bobbin winder is in operation. The bracket is mounted on the upright standard 11 for limited pivotal movement by means of the arm 22 which projects rearwardly from the arm 17 of the bracket and is pivotally connected to the standard by the screw or pin 23.

Depending from the base 16 of the bracket is a fixedly mounted bifurcated arm 24 through which extends the pivot pin 25 for mounting a link 26 between the arms 24. The link 26 is pivotally connected at 27 to the shank of a button 28 mounted in a fixed support or plate 29. To move the pulley 21 into contact with the fly wheel 14, the operator slides the button 28 upwardly, producing slight pivotal movement of the bracket around the point 23; and to move the pulley out of engagement with the wheel 14, the operator merely depresses the button into the position shown in Fig. 2.

30 The inner end of the pulley shaft 20 has fixed to it a pinion 30 and the head stock 31 for rotating the spool 32. The pinion 30 meshes with a gear 33 fixed on the distributor shaft 34, the latter being rotatably mounted in bearings 35 and 36 in the bracket members 17 and 18, respectively. Opposite the head stock 31, in the upper portion of the bracket arm 18, is a tail stock 37 for engaging one end of the spool 32. The tail stock 37 is spring pressed by a coiled spring 38 located in a recess in the bracket arm 18, between the tail stock 37 and the side wall of the bracket arm, said spring being wrapped around the pin 39 on which the tail stock is mounted. 40 indicates means for withdrawing the tailstock 37 in order to position the spool 32.

The thread distributor arm 41 has a hook 42 on its upper end and an inturned right angle end 43 on its lower end. The distributor arm 41 is connected by a screw 44 to a block 45 provided with a circular bore for receiving the distributor shaft 34, and with a recess extending at right angles to the bore for receiving a rockable key 46, shown in perspective in Fig. 5, and in the sectional view, Fig. 4.

55 The rockable member 46 comprises a cylindri-

cal body having a reduced end which terminates in a key 47 provided with a curved face 48 adapted to engage the circumferential surfaces 49 produced on the shaft 34 by cutting two spiral guideways thereon as best shown in Figs. 3 and 6. The spiral guideways are connected with each other at opposite ends of the shaft 34.

The operation of the bobbin winder is as follows: the spool 32 intended to receive the thread 50 is positioned as shown in Fig. 3, between the rotatable head stock 31 and the spring pressed tail stock 37. When the pulley 21 has been moved into contact with the fly wheel 14 (which may be motor powered or treadle operated), the pulley 21 through its pinion 30 will drive the gear 33 on the distributor shaft 34 and rotate said shaft. The pulley 21 will also rotate the head stock 31 and spool 32. The rotation of the distributor shaft 34, due to the engagement of the key 47 of the rocker 46 in the guideway 49 of said shaft 34, will cause the distributor arm 41 to move longitudinally of said shaft 34, first in one direction and then in the opposite direction, while the rotating spool 32 will draw the thread 50 through the hooked end 42 of the distributor arm 41 as it passes back and forth across the spool.

The reciprocating movement of the distributor arm 41 is positively controlled by the uniformly spiral guideways 49 in which the key 47 of the rocker member 46 is guided. It will be understood that the rocker action of the rocker 46 in the block 45 permits the key 47 to be tilted to one side to travel in the spiral guideway in one direction and to be tilted to the other side in order to travel in the spiral guideway in the opposite direction.

The fact that the spool 32 and the distributor shaft 34 are positively driven by gearing actuated from the same pulley shaft results in dependable synchronization of the winding mechanism, whereby the thread is smoothly and evenly placed in uniform rows, without strain on the thread. Changes may be made in details of construction and form of parts without departing from the scope of my invention as set forth in the appended claims.

I claim:

1. In a sewing machine provided with an upright standard and a rotatable fly wheel, a bobbin winder comprising a rigid bracket having a rearwardly extending arm pivotally connected to said standard in juxtaposition to said fly wheel, a link pivotally connected at one end to said bracket, a manually actuated member mounted for limited movement in a fixed part of the standard, said manually actuated member being pivotally connected to the opposite end of the link, spool holding means rotatably mounted in the bracket, a shaft mounted in the bracket in axial alignment with the spool holding means and connected thereto for rotating said means, a pulley on said shaft, manipulation of said manually actuated member serving to move said pulley into and out of engagement with said fly wheel, a distributor shaft mounted in the bracket parallel with the spool holding means, a thread distributor arm mounted on the distributor shaft, cooperating means on the arm and shaft for caus-

ing the arm to move longitudinally of the shaft when the shaft is rotated, and means on the distributor shaft operatively connected with the shaft which rotates the spool holding means for rotating the distributor shaft in timed relation to the rotation of the spool holding means.

2. In a sewing machine provided with an upright standard and a rotatable fly wheel, bobbin winder mechanism comprising a bracket pivotally mounted on said standard, spool holder means rotatably mounted in said bracket, means carried by the bracket and actuated by direct contact with the fly wheel for rotating said spool holder means, a distributor shaft parallel with the spool holder means rotatably mounted in the bracket, a thread distributor arm mounted on the distributor shaft, cooperating means on the arm and shaft for causing the arm to move longitudinally of the shaft when the shaft is rotated, means on the distributor shaft operatively connected with the spool holder rotating means for rotating the distributor shaft in timed relation to the rotation of the spool holder means, and manually operable means mounted on the standard and pivotally connected to the bracket for moving the bracket and thereby moving the spool holder rotating means into and out of contact with the fly wheel.

3. In a sewing machine provided with an upright standard and a rotatable fly wheel, a bobbin winder comprising a bracket pivotally mounted on the face of said standard slightly below the axis of the fly wheel, spool holding means rotatably mounted in said bracket, a pulley rotatably mounted on the bracket and actuated by direct contact with the fly wheel, said pulley being operatively connected with the spool holding means for rotating said means, a distributor shaft rotatably mounted in the bracket parallel with the spool holding means, a thread distributor arm mounted on the distributor shaft, cooperating means on the arm and shaft for causing the arm to move longitudinally of the shaft when the shaft is rotated, means on the distributor shaft operatively connected with the pulley for rotating the distributor shaft in timed relation to the rotation of the spool holding means when said pulley is in contact with the fly wheel, and manually actuated means for moving the bracket and thereby moving the pulley into and out of driving engagement with the fly wheel.
